DESIGN FOR A COMBINED TOBACCO BLENDER AND HUMIDOR

John Russell, Sr., Summit, N. J.

Application February 24, 1944, Serial No. 112,691

Term of patent 3½ years

(Cl. D85—2)

To all whom it may concern:

Be it known that I, John Russell, Sr., a citizen of the United States and a resident of Summit, in the county of Union and State of New Jersey, have invented a new, original, and ornamental Design for a Combined Tobacco Blender and Humidor, of which the following is a specification, references being had to the accompanying drawing, forming part thereof.

Figure 1 is a top plan view of a combined to-

bacco blender and humidor showing my new design.

Figure 2 is a front elevational view and Figure 3 is a side elevational view of the combined tobacco blender and humidor.

I claim:

The ornamental design for a combined tobacco blender and humidor, as shown.

JOHN RUSSELL, SR.
